UNITED STATES PATENT OFFICE.

ROBERT ALLEN, OF OXON, ENGLAND.

METALLIC PACKING FOR PISTONS.

Application filed April 7, 1923. Serial No. 630,572.

To all whom it may concern:

Be it known that I, ROBERT ALLEN, of Chiltern Rise, Woodcote, Oxon, England (whose post-office address is Chiltern Rise, 5 Woodcote, Oxon, England), a subject of the King of Great Britain and Ireland, have invented certain new and useful Improvements in Metallic Packings for Pistons, of which the following is a specification.

10 This invention relates to metallic packing for pistons and the like, and is applicable to the pistons of internal combustion engines, steam engines, compressors and in general to all pistons where it is desired to 15 provide an effective seal between the piston and its surrounding cylinder wall.

According to this invention, each packing unit comprises a pair of split rings arranged side by side in the same groove with 20 their joints or splits diametrically opposed, and joint or split closing or choke pieces adapted to prevent leakage of pressure fluid through the splits in the rings, said choke pieces being pressed outwards radially by 25 springs and each engaging the split part of one ring and the neutral part of the other ring, that is to say, the part diametrically opposite the split or joint of the ring. Each choke piece is also formed or provided in 30 known manner with a projection or stop for engaging in the split portion or gap of the ring, and preventing the ring from turning in its groove.

In the accompanying three sheets of 35 illustrative drawings:

Figs. 1 and 2 are a longitudinal and transverse section respectively of a piston with packing constructed according to this invention,

40 Figs. 3 and 4 are similar views to Figs. 1 and 2, showing a slightly modified form of construction and

Figs. 5 and 6 are elevations at right angles of one of the split packing rings,

45 Fig. 7 illustrates in end, side and sectional detail views a socket provided in some cases for holding the split-closing piece or choke and its spring,

Figs. 8 and 9 are detail views of split- 50 closing pieces or chokes.

Figs. 1 and 2 show a piston *a* provided with two sets of packing rings, *b*, *b'*, *c*, *c'* each equipped with a pair of diametrically opposite radial choke pieces or spring plungers *d*, *d'* of cylindrical form arranged in radial 55 pockets or recesses *e*, *e'* bored in the piston. It will be seen that the axes of the opposite choke pieces are not in alignment, being preferably arranged so that the part of the pocket or recess from which a joint or split 60 closing segment *f* of the choke projects, is cut entirely in the side wall of the groove. Each choke piece *d*, *d'* is recessed at its outer end to a depth corresponding with the groove in the piston and under the influence 65 of its spring *g* presses outwardly on both packing rings, the said choke being located opposite the split portion of one ring which is closed thereby and opposite that part of the other ring which is diametrically opposite 70 its split, the result being that both rings are pressed outwards by the two plungers or choke pieces both at their joints or split portions, and at their opposite or neutral points, and by this means close contact 75 between the rings and cylinder wall at all parts of the periphery is ensured.

A stop *h* is either formed on the choke plunger as clearly shown in Fig. 8 or may be attached in the form of a stud as shown 80 in Fig. 9. The stop *h* is intended by engaging an enlargement *i* of the split (Fig. 5) to prevent the split ring from turning in its groove.

In some cases as shown in Figs. 3 and 4 and 85 Fig. 7, socket pieces *j* for the reception of the chokes *d*, *d'* may be secured in radial holes bored in the piston body, the walls of the sockets being enlarged at their open or outer ends to form shoulders *j'* which rest 90 against shoulders formed by counter-boring the radial holes. The enlarged outer ends of the socket pieces are also grooved or recessed as at *k*, to accommodate the packing rings.

I claim:

The combination with a piston or the like having a packing groove and recesses opening into said groove at diametrically opposite points, of a pair of split packing rings 100

2
arranged in said groove, side by side, and with their joints diametrically opposite and disposed over said recesses, spring-pressed 5 plungers mounted in said recesses, each of said plungers being provided with a portion pressing against the intermediate portion of one ring and with another projecting por-

tion disposed between and pressing against the ends of the other ring, whereby both rings are maintained expanded but are 10 locked against rotation in said groove.

In testimony whereof he has affixed his signature.

ROBERT ALLEN.
